MAST CRADLE OR THE LIKE

Hayne Palmour III, 2707 Mayview Road,
Raleigh, N.C. 27607

Filed July 12, 1974, Ser. No. 488,052

Term of patent 14 years

Int. Cl. D12—99

U.S. Cl. D12—155

FIG. 1

FIG. 2

FIG. 3

FIG. 4

FIG. 5

FIG. 6

FIG. 7

FIG. 8

FIG. 9

FIG. 10

FIG. 1 is a perspective view of the mast cradle or the like showing my new design;

FIG. 2 is a front elevational view of such design, the rear view being substantially a mirror image thereof;

FIG. 3 is a right side view of such design, the opposite side being substantially a mirror image of that shown;

FIG. 4 is a top plan view of the design;

FIG. 5 is a bottom view of the same;

FIG. 6 is a perspective view of a modification of the mast cradle or the like showing my new design;

FIG. 7 is a front elevational view of such modification, the rear view thereof being substantially a mirror image of that shown;

FIG. 8 is a right side view of such modification, the opposite side being substantially a mirror image of that shown;

FIG. 9 is a top plan view of the modification; and FIG. 10 is a bottom plan view of the same.

I claim:

The ornamental design for a mast cradle or the like, as shown and described.
